C. W. DUCKWORTH

VAPORIZER

Filed Sept. 4, 1923

FIG 2

FIG 3

Charles W. Duckworth,

Inventor

by: *Henry J. Schmidt*
his Attorney.

Patented July 22, 1924.

UNITED STATES PATENT OFFICE.

CHARLES W. DUCKWORTH, OF JACKSONVILLE, FLORIDA.

VAPORIZER.

Application filed September 4, 1923. Serial No. 660,769.

To all whom it may concern:

Be it known that I, CHARLES W. DUCKWORTH, a citizen of the United States, residing at Jacksonville, in the county of Duval and State of Florida, have invented certain new and useful Improvements in Vaporizers, of which the following is a specification.

My invention relates to vaporizers of the class used for vaporizing the fuels used in internal combustion engines. The main and particular objects and advantages of the invention are: To provide a vaporizer in which the fuel, as it passes through it to the engine, is vaporized by the heat given off by the exhaust from the engine; to provide means for adding additional heated or cold air to the fuel; and to provide means for thoroughly mixing this added air with the fuel.

20 A further object is to provide a vaporizer automatic in its operation, simple in construction, small in size, easy to attach to any engine, and comparatively inexpensive to manufacture.

25 These and various other objects and advantages will be clearly understood from the following specification and from the accompanying drawing of a preferred embodiment of my invention, but it will be understood that modifications might be made without departing from the scope of the invention.

Fig. 1 is a side elevation of a preferred embodiment of the vaporizer.

35 Fig. 2 is a cross-sectional top view of Fig. 1, taken on the line 2—2. Several of the inner tubes having been omitted.

Fig. 3 is a cross-sectional end view of Fig. 1, taken on the line 3—3. Several of the 40 tubes having been omitted.

In the description which follows, the operation of the vaporizer has been explained in connection with a gasoline, automobile engine to facilitate the description, but it will be understood that I do not wish to limit the use of the invention to such engines only.

In a general way the vaporizer may be described as a device placed between the carburetor and the engine; the air and gasoline, after being mixed in the carburetor, enters the vaporizer where this mixture is heated by passing through a plurality of tubes, heated by the exhaust from the engine. Additional air is drawn into the va-

porizer and mixed with the heated mixture before it enters the engine.

Referring now to all the views, the vaporizer consists of an exhaust inlet part 4, an exhaust outlet part 5 and two air inlet parts 6 and 7. The parts 4 and 5 are similar but turned in opposite directions and so are the parts 6 and 7. All these parts are similar in shape and size to the boss on the engine and are bolted between the carburetor and the engine by means of cap screws passing through the holes 8 and 9. These holes extend through all four parts and as they align with the holes in the carburetor and engine, no drilling or tapping in either of these is necessary.

The exhaust inlet part 4 and the exhaust outlet part 5 are each provided with internally threaded branches 10, 11 and 12, 13 respectively. On the sides facing each other, these parts are also provided with circular recesses, so that when the two parts are assembled a chamber 14 is formed. The inlets 10 and 11 communicate with this chamber through the openings 15 and 16, while the outlets 12 and 13 communicate with the chamber through the openings 17 and 18. Inside the chamber 14 a plurality of tubes 19 are placed; these tubes are riveted between the parts 4 and 5 and are open at both ends, as plainly shown on Figs. 2 and 3. However, only a few of these tubes are shown in Figs. 2 and 3.

The air inlet part 7 has a conical opening, the large end of which is placed adjacent to the exhaust inlet part 4. An air distribution chamber 21 is formed in the conical opening 20 by turning a recess in this opening and covering it with a conical washer 22. This washer is so constructed that it forms part 90 of the opening 20 and is perforated by a plurality of small, air holes 23. An internally threaded air inlet 24 is provided on the periphery of part 7 and an air passage 25 connects this inlet with the air distribution chamber 21. A wire mesh screen 26 is also placed in the opening 20. The air inlet part 6 is likewise provided with a conical opening 27, an air distribution chamber 28, a washer 29 having perforations 30, an internally threaded air inlet 31, an air passage 32 and a wire mesh screen 33.

The conical openings 20 and 27 are so proportioned that their small ends correspond in size to the openings in the carburetor and

engine, while their large ends extend outside of outermost tubes 19, thus offering a free passage for the engine fuel through opening 20, tubes 19 and opening 27. The number and size of the tubes are preferable such as not to retard the flow of the fuel through the vaporizer.

The vaporizer works in the following manner: Part of the exhaust from the engine is conveyed to the branches 10 and 11 by suitable piping. The exhaust after flowing through the branches enters the chamber through the openings 15 and 16 and heats the tubes 19. From the chamber 14 the exhaust is expelled through the openings 17, 18 and branches 12, 13. Suitable piping, fitted in these branches, convey the used exhaust to such place where it is desired to exhaust it.

10 The mixture of gasoline and air, after leaving the carburetor, flows through the opening 20 and is mixed with additional air drawn through the air inlet 24, air passage 25, air distribution chamber 21 and perforations 23. The wire mesh screen interposed in the opening causes the mixture and added air to thoroughly mix. The fuel now flows through the tubes 19 where it is heated to complete vaporization and finally through 15 the opening 27 into the engine. In passing through the opening 27 air, when needed, is drawn through the perforations 30.

20 It will be noted that the air drawn from the chamber 21 is heated by passing through the tubes 19 with the rest of the fuel, while the air drawn from the chamber 28 does not pass through these tubes, thus it is possible to supply either hot or cold air or both.

25 Manually operated air valves may be attached in either one or both of the air in-

lets 24 and 31, or automatic air valves may be used.

Having thus described my invention and its operation what I claim as new and wish to protect by Letters Patent is:

45 1. In a vaporizer of the class described; an inner part having a chamber with one or more inlets and outlets through which the exhaust from the engine flows; a plurality of tubes placed in said chamber and heated by the exhaust; a fuel inlet part having a conical opening communicating with the said tubes; an air inlet in said fuel inlet part; a screen interposed in said conical opening; a fuel outlet part for guiding the vaporized fuel into the engine; an air inlet in said fuel outlet part; and means for attaching the vaporizer.

50 2. In a vaporizer of the class described; an inner part having a chamber with one or more inlets and outlets through which the exhaust from the engine flows; a plurality of tubes placed in said chamber and heated by the exhaust; a fuel inlet having a conical opening communicating with said tubes; a fuel outlet for guiding the vaporized fuel into the engine; air inlets in said fuel inlet and outlet; means for distributing the air from said air inlets evenly; screens interposed in the fuel inlet and outlet for mixing the added air with the fuel; and means for attaching the vaporizer.

55 In testimony whereof I, CHARLES W. DUCKWORTH have signed my name to this specification in the presence of two subscribing witnesses, this 17th day of Oct. 1922.

70 CHARLES W. DUCKWORTH.
